UNITED STATES PATENT OFFICE.

SAMUEL J. WEBB, OF MINDEN, LOUISIANA.

HYDRAULIC PRESS WITH DOUBLE-PISTON RAM.

No. 836,350.

Specification of Letters Patent.

Patented Nov. 20, 1906.

Application filed April 5, 1901. Serial No. 54,536.

To all whom it may concern:

Be it known that I, SAMUEL J. WEBB, a citizen of the United States, residing at Minden, in the parish of Webster and State of Louisiana, have invented certain new and useful Improvements in Hydraulic Presses with Double-Piston Rams, of which the following is a specification.

My invention relates to hydraulic presses for compressing cotton and other similar materials, and it has for its object to provide an improved construction and arrangement of hydraulic-press involving more particularly what may be termed a "double-piston ram" operating in connection with the press proper; and to these ends my invention consists in the various features of construction and arrangement of parts, having the general mode of operation substantially as hereinafter more particularly pointed out.

Referring to the accompanying drawings, Figure 1 is a vertical section of the double-piston ram, showing the parts in what may be termed their "normal" positions. Fig. 2 is a similar sectional view of the double-piston ram, showing the parts in another position. Fig. 3 is a vertical section of a press proper, which in this instance is shown connected to the double-piston ram of Fig. 2. Fig. 4 is an enlarged inverted plan view showing the rock-shafts with an arrangement of cams suitable for operating the various valves, these being shown on a slightly enlarged scale for the purpose of clearness. Fig. 5 is a perspective view of the valve arrangement shown in Figs. 2 and 4. Fig. 6 is a side view of the valves and operating devices therefor. Fig. 7 is a sectional view showing the preferred construction of the valves, and Fig. 8 is a plan view of the distance-piece.

In carrying out my invention it will be understood that the hydraulic press proper may vary in construction, that shown in the drawings being for the purposes of illustration and being one well adapted for use in connection with a double-piston ram, and it is to be understood that my invention is not limited to the use of the particular press shown and described. This press A consists, generally stated, of a stationary body or platen A', which is connected by suitable rods, as A², to the hydraulic cylinder A³, which is suitably mounted or supported on a proper base A⁴. This hydraulic cylinder A³ may have any desired number of cylinders A⁵, two

being shown in the present instance, connected at the bottom by a passage A⁶. Mounted in these two cylinders A⁵ are the rams A⁷, which may be of any desired construction, but which in the present instance are shown as hollow rams of a length slightly less than the length of the cylinders A⁵.

Connected to move in connection with the stationary bed or platen A' is a movable bed or platen A⁸, and this in the present instance is guided by the rods A² and is connected to the rams A⁷, and while the connections may vary, in the present instance I have shown distance-pieces A⁹ recessed on their upper faces and adapted to fit projections A¹⁰ on the under side of the movable platen A⁸ and having similar projections A¹¹ adapted to fit corresponding recesses in the tops of the rams A⁷. These projections are not absolutely necessary, but are advantageous in locating and holding the parts together, and in the present instance I have shown screw rods or bolts A¹², the heads being countersunk in the top of the movable platen A⁸ and their stems passing through openings in the distance-pieces and taking into screw-threaded openings in the tops of the rams. These distance-pieces A⁹ are preferably provided with slots w, extending from their central opening to one side, so that when the screw-bolts A¹² are loosened the distance-pieces A⁹ can be removed and the screw-bolts A¹² operated so as to permit the rams A⁷ to descend to the lowermost position in the cylinders A⁵, exposing the packing-rings A¹³ in the upper portions of the cylinders, so that they can be readily manipulated for adjustment or repairs, the platen A⁸ being held or blocked up enough to clear the distance-pieces while this is being done.

The movable platen A⁸ in the present instance is shown as provided with a grooved bed-plate A¹⁴, which may be removably supported on the moving platen A⁸, but preferably, as shown in the present instance, the plate is made in three sections and the side sections A¹⁵ A¹⁶ may be removed without necessarily removing the central section to get at the heads of the bolts A¹².

The double-piston hydraulic ram as shown in the present instance consists, essentially, of a case or motor or power cylinder B, having two cylinder-heads B' B², and mounted on the cylinder-head B' is a second cylinder B³, having a head B⁴, and this head in the present instance is provided with an inwardly-

extending projection B^5 , and may be made of any desired length, but preferably about one-fourth the length of the stroke, as shown. Mounted in the cylinder B is a low-pressure piston C , to which is attached or formed integral therewith a ram C' , having a piston-head C^2 , working in the cylinder B^3 . This ram is itself cylindrical and hollow and forms a hydraulic cylinder D for the ram D' , mounted on the high-pressure piston D^2 , working in the cylinder B , and arranged in the present instance so that the ram D' passes through a central opening C^4 in the piston C and the ram C' . This cylinder D in the ram C' is of a size to receive the projection B^5 when the parts are in the positions shown in Fig. 2. The stems of the rams C' D' are provided with heads and packings so as to avoid exposing the stems to the liquid and heating the liquid in the cylinders, which it is important to avoid when the same liquid is used continuously. In operating hydraulic rams of this character it is essential to provide some means for cushioning the parts to prevent accidents from shocks, &c., especially when they are rigidly operated, and in the present instance all the moving parts of the pistons and rams are so provided. For instance, the low-pressure piston C is provided with a projection C^5 , which is adapted to fit more or less closely in the cylinder B^3 and form a cushion when the piston is moved upward by cutting off the escape through the vent-pipe, herein-after described. This piston is also formed with a recess C^6 in the under side, which is adapted to receive a projection D^3 on the upper side of the high-pressure piston D^2 , and this high-pressure piston is further provided with a projection D^4 on its under side, adapted to enter a recess B^6 in the head B^2 , controlling the exhaust from the cylinder. Furthermore, the ram C' , which, as before stated, receives the projection B^5 , serves as a cushion by cutting off the main outlet from the cylinder B^3 .

All the parts of the pistons and rams are provided with suitable packing, as indicated. Thus the low-pressure piston C is provided with packing c , the ram C' with packing c' . The piston D^2 is provided with packing d , and the central opening C^4 in the piston C , through which the ram D' passes, is provided with packing d' . So also the recess C^6 in the piston C , and the recess B^6 in the head B^2 and head B^1 are provided with packing, as indicated but not specifically lettered.

The cylinder B^3 is provided with a port B^7 , which in the present instance is shown in the form of a passage through the projection B^5 , and connected to this port is a pipe E , leading to the hydraulic cylinder A^3 of the press A and shown in the present instance as connected to the passage A^6 thereof at the point E' . No valve need be supplied to this pipe between the cylinder B^3 and cylinders A^5 , as

the water or other fluid contained in the pipe and cylinders is used over and over, being drawn forward or backward in operating the press, and communication between the press cylinders A^5 and the low-pressure cylinder B^3 of the ram is cut off when the low-pressure piston C and its ram C' are in the positions shown in Fig. 2, or in the latter part of its stroke by the projection B^5 entering the cylinder D . 75

In order that the low-pressure ram C' may attain the position shown in Fig. 2, the projection B^5 enters the cylinder D and thereby cuts off the flow of fluid through the port B^7 , and the pipe E is provided with a by-pass G , connecting the head B^4 of the cylinder and the pipe E and provided with a valve G' , which opens automatically under pressure to allow the fluid to flow from the top of the cylinder B^3 into the pipe E , and may be in the form of a simple check-valve. In order, however, to provide means to allow the ram C' to move from the position shown in Fig. 2, it is necessary to allow fluid to pass into the top end of the cylinder B^3 , and I accomplish this by providing some means of operating the valve in the by-pass G , and in the present instance I have shown a lever G^2 , having a cam g , adapted to open the check or other valve G . 85 90 95

The pistons in the present instance are adapted to be operated by steam-pressure, and I therefore provide a suitable steam-pipe H , connected with any source of supply, and from this main steam-pipe leads a pipe H' to a pipe I , attached to the head B^2 , and connected to the high-pressure piston D^2 is a pipe I' , which reciprocates with the piston and moves up and down in the pipe I . This pipe I' is suitably connected so as to deliver steam between the low and high pressure pistons C and D^2 , and in the present instance the ram D' is made hollow at its lower portion D^5 and the pipe I' is connected thereto, while an opening or openings d^6 are made in the ram D' to permit steam to pass out of the hollow extension D^5 . Also leading from the steam-pipe H is a pipe H^2 , which in the present instance is shown as entering the recess B^6 in the cylinder B below the high-pressure piston D^2 . There is an exhaust-pipe H^3 connected to the steam-pipe H' by a pipe H^4 and to the steam-pipe H^2 by a pipe H^5 , and interposed in the pipes are suitable steam-valves G^3 G^6 and exhaust-valves G^4 G^5 , and these valves may be controlled in any suitable way, as by the levers J J' , mounted on a bracket J^2 on the press proper. In the present instance I have shown two rock-shafts J^3 J^4 , provided, respectively, with levers J^5 J^6 and having suitable cams g^3 g^4 g^5 g^6 . These levers J^5 J^6 are respectively connected to the operating-levers J' and J by any suitable means, as the connecting-links J^8 J^7 . So also the operating-lever J' is connected to op- 100 105 110 115 120 125 130

erate the valve G' in any suitable way, as by the connecting-rod J^9 , lever J^{10} , and rod J^{11} , connected to lever G^2 . There is a pipe K connected to the head B' of the cylinder B , which serves as an air-vent through which air may flow to and from the cylinder B , above the low-pressure piston C , the upward flow of air being cut off by the projection C^5 when it moves upward, entering the opening in the head B' , so that the movement of the low-pressure piston upward is properly cushioned, as before set forth.

Such being the preferred construction and arrangement of parts, when the parts of the ram are in the positions shown in Fig. 1 and it is desired to operate the movable platen A^8 of the press A , I first operate the low-pressure piston C by admitting steam between the two pistons C and D^2 . In order to do this in the present arrangement, the hand-operating-lever J is moved in the proper direction, (toward the point 6, Fig. 3,) so as to operate the valve G^6 and admit steam into the pipe I , which steam passes through the pipe I' , through the hollow portion D^5 of the ram D' , and out through the opening or openings d^5 between the pistons, and the piston C is forced up to about the position indicated in Fig. 2. In doing this the ram C' has forced the fluid from the cylinder B^3 through the pipe E into the hydraulic cylinders A^5 , operating their rams A^7 , lifting the movable platen A^8 , and compressing the material between the platens. In doing this, as the ram C' passes over the projection B^5 the flow of fluid through the port B^7 is cut off; but the pressure in the end of the cylinder opens the check-valve G' in the by-pass G , and the fluid continues to flow through the pipe E . When the projection C^5 enters the opening in the head B' and cuts off the flow of air through the pipe K , a portion of the air is confined between the head B' and the top of the piston C , forming a cushion. The valve G^6 is closed by moving the lever J to the left to its normal position. The lever J' is then moved to the right to the point indicated by 3 in the arc above the lever, and this operates rock-shaft J^3 and through the medium of the cam g^3 opens the steam-valve G^3 , and steam is admitted through the pipe H^2 under the high-pressure piston D^2 , and this is forced upward, driving the ram D' , with its head D^6 in the cylinder D of the ram C' , forcing the fluid therefrom into the pipe E , and owing to the relative size of the piston D^2 and the head D^6 of the ram D' the fluid-pressure is largely increased, and the rams A^7 are forced upward under this final pressure, completing the pressure on the bale or other material between the platens. Coincident with the opening of steam-valve G^3 one of the cams g^4 on the rock-shaft J^3 has been operated to a greater or less extent, so as to partially at least operate exhaust-valve G^4 , so as to per-

mit more or less of the steam between the pistons C and D^2 to escape and offer no resistance to the movement of the piston D^2 ; but sufficient is retained to sustain the weight of piston C when the ram is worked in a vertical position, as shown in the drawings, but this is not necessary if the ram is worked horizontally, and the lever J' can be moved to the right beyond the point 3 in the arc, as to the point 4, in completely exhausting the steam between the pistons C and D^2 when it is desired to do so. When the pressure upon the bale is complete, the lever J' is returned to its normal position shown and all the valves are closed, while the material, as the bale of cotton, is being manipulated—as, for instance, being banded. When this is being accomplished, the lever J' is moved to the left to the points indicated by the numerals 1, 5, and 4 on the arc above the lever, and in doing this check-valve G' is opened by the cam on the lever G^2 , the exhaust-valve G^5 is opened by the cam g^5 on the rock-shaft J^3 , and the exhaust-valve G^4 is opened by the other portion of the double cam g^4 on the rock-shaft J^3 , which allows all the steam to escape and the parts to return to their normal positions. It will be observed that there is no back pressure of fluid from the pipe E on the ram C' tending to cause the low-pressure piston to descend, as this pressure is cut off by the projection B^5 entering the ram C' , and the check-valve G' prevents the backward flow of the fluid through the by-pass pipe G . When the bale or other material has been sufficiently compressed, which may be when the pistons are at any points of their stroke, the exhaust-valves G^4 and G^5 are opened by the movement of the hand-operating lever J' , and at the same time the check-valve G' is opened and the pistons C and D^2 fall to their normal positions, (shown in Fig. 1,) and the fluid in the hydraulic cylinders A^5 flows back into the cylinders B^3 and D , and the platen A^8 assumes its normal position. It will thus be seen that by the pipe connections and valves or control means shown the steam may be admitted or exhausted with the pistons at any points of their strokes.

When it is desired to pack the rams A^7 , the platen A^8 is blocked up high enough to clear the distance-pieces A^9 , the side sections A^{15} of the plate A^{14} may be removed, the screws A^{12} loosened, and the distance-pieces A^9 removed, and then the rams A^7 , being shorter than the cylinders A^5 , will while resting on the bottom of said cylinders permit access to the packing-rings A^{13} .

It may be remarked that instead of using separate distance-pieces A^9 , these may be in the form of integral projections on the under side of the platen A^8 .

In actual practice I preferably make the ram C' tapering, being thicker at its end most distant from the piston C , where the greatest

pressure is upon the hydraulic cylinder D inside the ram, and this conduces to lightness and cheapness and provides strength at the proper place. So, too, I preferably make the ram D' with a body portion smaller than the cylinder D, so as to leave a space between them to prevent radiation of heat, the head D⁶ of the ram of course fitting closely the cylinder D and being provided with proper packing d⁶.

In order that the hydraulic cylinder B³ may be kept cool, I preferably provide a narrow bearing-surface b at the end where it rests on the head B', and also surround it with a water-jacket b'.

What I claim is—

1. In a hydraulic press, the combination with a hydraulic cylinder, of a movable platen, a plurality of rams operating in the hydraulic cylinder, bolts connecting the platen with the respective rams, and a sectional plate secured to the platen to cover said bolts, whereby the removal of one section of the plate will afford access to the connecting-bolts of one or another of the rams, substantially as set forth.

2. In a hydraulic ram, the combination with a cylinder, of two pistons working in the cylinder, one of the pistons having a recess and the other a projection serving as a cushioning device between their adjacent faces, substantially as described.

3. In a hydraulic ram, the combination with a cylinder, of two pistons working in the cylinder, pipe connections and valves for delivering steam to and from the space between the two pistons to operate one of the same and for delivering steam to and from the space behind the other piston, said valves being constructed and arranged to admit and exhaust steam to and from the space between the pistons when the same are at any point of their stroke, substantially as described.

4. In a hydraulic ram, the combination with a cylinder, of pistons working therein and having high and low pressure plungers attached thereto, pipe connections and valves for delivering steam between the pistons for operating the piston carrying the low-pressure plunger and behind the piston carrying the high-pressure plunger, said valves being constructed and arranged to admit and exhaust steam to and from the space between the pistons when the same are at any point of their stroke, substantially as described.

5. In a hydraulic ram, the combination with a steam-cylinder and a hydraulic cylinder connected thereto, of a high and a low pressure piston in the steam-cylinder, one of the pistons carrying a ram working in the hydraulic cylinder and the other piston carrying a piston-head working in the ram of the first piston, and means coacting with the low-pressure ram and in virtue of which the latter re-

lieves itself of back pressure after being carried a part of its stroke and is held in this position while the high-pressure piston is being operated to give the final pressure, substantially as described.

6. In a hydraulic ram, the combination with a steam-cylinder, and a hydraulic cylinder connected thereto, of two pistons working in the steam-cylinder, one of the pistons being provided with a hollow ram fitting the hydraulic cylinder, the other piston being provided with a ram fitting the hollow ram, a passage in one of said pistons, and a pipe connected thereto extending outside the steam-cylinder whereby steam may be delivered between the two pistons or exhausted therefrom when either of the pistons is in any position, substantially as described.

7. In a hydraulic ram, the combination with a steam-cylinder, and a hydraulic cylinder connected thereto having a hollow projection in its outer end, of a piston mounted in the steam-cylinder, a hollow hydraulic ram mounted thereon and adapted to embrace the projection in said cylinder, a pipe leading from said projection, and a by-pass provided with a valve connecting said pipe with the end of the cylinder, substantially as described.

8. In a hydraulic ram, the combination with a steam-cylinder, and a hydraulic cylinder connected thereto, of a high and a low pressure piston working in the steam-cylinder, a low-pressure hydraulic ram connected to one piston and forming a high-pressure cylinder, a high-pressure piston connected to the other piston and working in said high-pressure cylinder, and means for automatically cutting off the exhaust from the front of low-pressure steam-piston to form a cushion for said piston, and means for automatically cutting off the exhaust from between the pistons to form a cushion to prevent their striking each other, substantially as described.

9. In a hydraulic ram, the combination with a steam-cylinder, and a hydraulic cylinder connected thereto, of high and low pressure pistons in the steam-cylinder, a ram connected to each piston, and a steam-pipe connected to and moving with one of the pistons to deliver steam between the pistons and allow it to exhaust therefrom, substantially as described.

10. In a hydraulic ram, the combination with a steam-cylinder, and a hydraulic cylinder connected thereto, of high and low pressure pistons in the steam-cylinder, a ram connected to each piston, a steam-pipe connected to and moving with one of the pistons to deliver steam between the pistons, and allow it to exhaust therefrom, and a telescopic section connected to the steam-cylinder in which said pipe operates, substantially as described.

11. In a hydraulic machine, the combina-

- tion of a low-pressure hydraulic cylinder having a ram or plunger adapted to work therein and an opening communicating with the pipe leading to the apparatus to be operated, a high-pressure hydraulic cylinder having a ram or plunger adapted to work therein, means for operating them, and means whereby the low-pressure ram or plunger will cut off communication between the low-pressure cylinder and the apparatus to be operated and prevent pressure in the low-pressure cylinder while the high pressure is being applied to the other ram, substantially as described.
12. A hydraulic machine, having a hollow low-pressure ram fitting a hydraulic cylinder and a high-pressure ram adapted to work within the low-pressure ram, and means for preventing pressure on the forward end of the low-pressure ram while the high-pressure ram is being operated, substantially as described.
13. A hydraulic machine, having a hollow low-pressure ram fitting a hydraulic cylinder and a high-pressure ram adapted to work within the low-pressure ram, means for operating both rams, and means for preventing pressure on the forward end of the low-pressure ram while the high-pressure ram is being operated, substantially as described.
14. In a hydraulic ram, the combination with a motor-cylinder and a hydraulic cylinder connected thereto, of two pistons working in the motor-cylinder, the forward piston carrying a hollow ram fitting the hydraulic cylinder, the rear piston carrying a ram fitting the cylinder of the hollow ram, and means whereby the pressure in the low-pressure cylinder is cut off to prevent its ram from being forced back while the high pressure is being applied by the other ram, substantially as described.
15. In a hydraulic ram, the combination with a steam-cylinder and a hydraulic cylinder connected thereto, of pistons having a low-pressure plunger and a high-pressure plunger connected thereto, each piston working in the steam - cylinder, the low-pressure plunger being hollow and having a piston - head on its forward end fitting the hydraulic cylinder and bored to form a cylinder, the other plunger carrying a piston-head on its forward end and fitting the cylinder of the hollow plunger, and independent means for directing the motor fluid between and back of the pistons, substantially as described and for the purposes set forth.
16. In a hydraulic ram, the combination of a low-pressure cylinder having a ram adapted to work therein, said low-pressure ram having a piston or head at its outer end, a high-pressure cylinder having a ram adapted to work therein, independent motor-pistons and means for applying power thereto to operate the rams, and means coacting with the piston of the low-pressure ram whereby pressure is prevented in the low-pressure cylinder while the high-pressure ram is being operated, substantially as set forth.

In testimony whereof I have signed my name to this specification in the presence of two subscribing witnesses.
